UNITED STATES PATENT OFFICE.

FERDINAND HÜNERBEIN, OF RÜTTENSCHIED, GERMANY.

DECORATIVE SLAB.

No. 800,805.

Specification of Letters Patent.

Patented Oct. 3, 1905.

Application filed February 17, 1905. Serial No. 246,181.

To all whom it may concern:

Be it known that I, FERDINAND HÜNERBEIN, a subject of the German Emperor, residing at Rüttenscheid, in the Kingdom of Prussia, 5 Germany, have invented new and useful Improvements in Decorative Slabs, of which the following is a specification.

This invention relates to a decorative slab provided with a surface ornamentation of 10 novel construction.

In the accompanying drawings, Figure 1 is a face view of a slab embodying my invention; Fig. 2, a cross-section on line 2 2, Fig. 1; and Fig. 3 an enlarged section at right angles to 15 Fig. 2.

The letter *a* represents a wooden slab or backing provided with a plastic covering *b*. This covering is provided with a series of 20 raised parallel ribs *c*, separated by intervening parallel grooves. Each of these grooves

is not made continuous, but filled out or made solid for part of its length, the solid sections of the adjoining grooves being contiguous to form raised undulations *d*. These undulations are of the same height as the ribs *c* and intersect the same to form a raised interlaced surface. 25

What I claim is—

A decorative slab composed of a backing and a plastic covering provided with raised 30 ribs and discontinuous intervening grooves, the ungrooved parts being in a line or lines intersecting the lines of the ribs to form raised undulations, substantially as specified.

Signed by me at Düsseldorf, Germany, this 35 29th day of December, 1904.

FERDINAND HÜNERBEIN.
